The ornamental design for a multi-tissue box, as shown and described.

DESCRIPTION

FIG. 1 is a top plan view of a multi-tissue box in an unfolded configuration showing my new design;

FIG. 2 is a top, front, and right side perspective view thereof; and,

FIG. 3 is a top, front, and left side perspective view thereof. The broken line showing of the multi-tissue box represents a perforated surface and forms a part of the claimed design.
